UNITED STATES PATENT OFFICE.

AXEL MONSON, OF CHICAGO, ILLINOIS, ASSIGNOR TO UNIVERSAL STAMPING & MFG. CO., OF CHICAGO, ILLINOIS, A CORPORATION OF ILLINOIS.

EJECTOR FOR COIN-HANDLING MACHINES.

Application filed August 10, 1927. Serial No. 211,955.

This invention relates to coin handling mechanisms and particularly to coin payers and changers.

The main objects of this invention are to provide a coin handling mechanism having an improved form of ejector; to provide an improved form of ejector for ejecting the lowermost coin from a magazine wherein the coins are stacked vertically; to provide an ejector of this kind having improved means for supporting the coin being ejected substantially parallel to the other coins until it leaves the magazine; and to provide supporting means of this kind which will produce a minimum amount of friction on the lowermost coin in the stack on the retraction of the ejector.

An illustrative embodiment of this invention is shown in the accompanying drawing, 20 wherein:

Figure 1 is a transverse vertical section showing part of a coin payer and changer to which this invention is applied.

Fig. 2 is an enlarged detail in section of an 25 ejector and part of the magazine.

Fig. 3 is a section taken on the line 3—3 of Fig. 1.

Fig. 4 is a similar view, but showing the 30 ejector in its extended position and the coin ready to drop into the chute.

Fig. 5 is a fragmentary front elevation, taken from the right of Fig. 4.

Fig. 6 is a perspective of one of the ejectors.

The improved ejector to which this invention is applied is adapted for use in connection with various types of coin handling mechanisms but, in the specific form herein shown, it is applied to a coin payer or changer.

40 Inasmuch as this invention relates particularly to the ejector, certain parts of the machine not relating thereto and believed to be unnecessary to a complete understanding of the invention have been omitted from the drawings.

In the form shown, the coin payer and changer comprises a casing or housing 1, having an inclined delivery chute 2 arranged to receive coins 3, which are ejected 45 from a tray 4 by improved ejectors 5.

The casing 1 is preferably formed of metal and is provided in its upper end with an opening 6 for receiving the tray 4. Extending upwardly through the casing, is a partition 55 7, having a plurality of slots 8, through which

the ejectors extend for engagement with the lowermost coins in the tray 4.

The chute 2 is corrugated, as shown at 9, in order to minimize the bearing surface of the chute which is presented to the falling coins. At the lower end of the chute, is arranged a suitable coin receiving cup, not shown.

60 The tray 4 comprises a battery of tubular magazines 10 arranged side by side and rigidly secured to a back plate 11, which may be detachably secured to the casing in any suitable manner. The tubular magazines 10 are open at the front side, as shown at 12, permitting insertion of the operator's fingers to facilitate loading of the tray with coins. The 70 magazines vary in size to accommodate coins of different denominations. At the lower end of each magazine, the edges of the tubular wall adjacent the opening 12 are struck out to provide lugs 13 arranged to define an 75 outlet opening 14 through which the coins are ejected.

The lower end of the back plate 11 is bent to form a transverse shelf 15 which extends along the entire tray to provide a bottom for 80 the magazines. Formed in the shelf 15, is a plurality of slots 16 arranged to provide guideways for the ejectors 5, which are thereby guided through substantially the centers of the outlet openings 14.

85 In the form shown, each of the ejectors 5 comprises an arm, preferably a sheet metal stamping which is resiliently suspended adjacent its forward end by a spring 17 supported by a hanger 18 which extends through 90 the upper rear part of the casing 1. The lower ends of the springs 17 are secured to lugs 19 formed on the ejector arms 5.

The ejector arms are selectively actuated by a plurality of manually operated keys which 95 are not shown but which are well understood in the art.

100 Formed adjacent the forward end of each ejector arm, is a shoulder 20 which is adapted to engage the rim of the lowermost coin in the magazine for ejecting the coin upon the forward movement of the ejector arm. The ejector arm is normally held in a retracted position so as to position the shoulder 20 rearwardly of the lowermost coin, as shown in Fig. 1. If desired, the shoulder 20 may be formed so as to engage more than one coin at each operation.

105 Formed at the forward end of the ejector bar, is a finger 21 which offset laterally from 110

the normal plane of the arm 5. The extremity of the finger 21 projects upwardly to provide a tip 22 which is adapted to engage the lower face of the coin. The distance between the shoulder 20 and tip 22 is slightly greater than the radius of the coin to be ejected, so that the tip 22 engages the coin near the forward edge thereof and to one side of its center, as shown in Fig. 4. The finger 21 is offset laterally to permit the coin to freely drop from the ejector after it has been moved beyond the shelf 15. If the tip 22 were located in alignment with the arm 5, the coin might sometimes remain balanced on the finger instead of dropping onto the chute 2. The greater portion of the finger 21 is offset below the finger 22 and shoulder 20 as shown at 23, so as to be out of contact with the coin. This improved construction minimizes the bearing surface of the ejector which is presented to the next succeeding lowermost coin upon the retraction of the ejector. Formed in the shelf 15, adjacent each guide slot 16, is a recess 24, arranged to receive the tip 22 of the adjacent finger 21 when the respective ejector bar is retracted.

In operation, the ejectors 5 are operated selectively by the keys, not shown. Upon the forward movement of any ejector, the shoulder 20 moves forwardly through the respective slot 16 in engagement with the rear edge of the coin. The tip 22 engages the lower face of the coin for holding the coin substantially parallel to the other coins in the magazine. When the coin reaches the position shown in Fig. 4, so as to be out of contact with the shelf 15 and the next succeeding coin, it tips to one side and drops onto the chute 2. The stack of coins then drops in the magazine so as to position the next succeeding coin on the shelf 15. Due to the weight of the stack of coins, upon the retraction of the ejector the arm 5 is moved downwardly against the action of the spring 17, thereby causing the upper edge of the arm to slidably engage the lower face of the stack. By reason of the offset position of the finger 21, the friction between the ejector and the stack of coins is reduced to a minimum.

Although but one specific embodiment of this invention has been herein shown and described, it will be understood that certain details of the construction shown may be altered or omitted without departing from the spirit of this invention as defined by the following claims.

I claim:

1. The combination with a coin handling mechanism having a magazine provided with an outlet, of an ejector comprising an arm movable transversely to said outlet, a shoulder on said arm adapted to engage the rim of a coin supported in said outlet, and a finger projecting beyond said shoulder and having a tip for engagement with the lower face of

the coin, said tip being offset from said finger for holding the coin out of engagement with the greater part of said finger.

2. The combination with a coin handling mechanism having a magazine provided with an outlet, of an ejector comprising an arm movable transversely to said outlet, a shoulder on said arm adapted to engage the rim of a coin supported in said outlet, and a finger projecting beyond said shoulder and having an offset tip for engagement with the lower face of the coin, the distance between said shoulder and tip being greater than the radius of the coin to be ejected.

3. The combination with a coin handling mechanism having a magazine provided with an outlet, of an ejector comprising an arm movable transversely to said outlet, a shoulder on said arm adapted to engage the rim of a coin supported in said outlet, and a finger projecting beyond said shoulder and having a tip for engagement with the lower face of the coin, said finger being offset from said shoulder and tip.

4. The combination with a coin handling mechanism having a magazine provided with an outlet, of an ejector comprising an arm movable transversely to said outlet, a shoulder on said arm adapted to engage the rim of a coin supported in said outlet, and a finger projecting beyond said shoulder and having a tip for engagement with the lower face of the coin, said finger being offset from said shoulder and tip, and the distance between said shoulder and tip being greater than the radius of the coin whereby said tip is adapted to engage the coin only at a point in advance of the center of the coin.

5. The combination with a coin handling mechanism having a magazine provided with an outlet, of an ejector comprising an arm movable transversely to said outlet, a shoulder on said arm adapted to engage the rim of a coin supported in said outlet, and a finger projecting beyond said shoulder and having a tip for engagement with the lower face of the coin, said finger being offset downwardly from said shoulder and tip.

6. The combination with a coin handling mechanism having a magazine provided with an outlet, of an ejector comprising an arm movable transversely to said outlet, a shoulder on said arm adapted to engage the rim of a coin supported in said outlet, and a finger projecting beyond said shoulder for engagement with the lower face of the coin, said finger being offset laterally from the plane of said arm and shoulder.

7. The combination with a coin handling mechanism having a magazine provided with an outlet, of an ejector comprising an arm movable transversely to said outlet, a shoulder on said arm adapted to engage the rim of a coin supported in said outlet, and a finger projecting beyond said shoulder and having

a tip for engagement with the lower face of the coin, said tip being offset laterally from the plane of said arm and shoulder.

8. The combination with a coin handling mechanism having a magazine provided with an outlet, of an ejector comprising an arm movable transversely to said outlet, a shoulder on said arm adapted to engage the rim of a coin supported in said outlet, and a finger projecting beyond said shoulder for engagement with the lower face of the coin, said finger being located on one side of the center of said outlet.

9. The combination with a coin handling mechanism having a magazine provided with an outlet, of an ejector comprising an arm movable transversely to said outlet, a shoulder on said arm adapted to engage the rim of a coin supported in said outlet, and a finger projecting beyond said shoulder and having a tip for engagement with the lower face of the coin, said tip being offset laterally from the center of said outlet.

10. The combination with a coin handling

mechanism having a magazine provided with an outlet, of an ejector comprising an arm movable transversely to said outlet, a shoulder on said arm adapted to engage the rim of a coin supported in said outlet, and a finger projecting beyond said shoulder for engagement with the lower face of the coin, said finger being offset laterally and downwardly from said arm.

11. The combination with a coin handling mechanism having a magazine provided with an outlet, of an ejector comprising an arm movable transversely to said outlet, a shoulder on said arm adapted to engage the rim of a coin supported in said outlet, and a finger projecting beyond said shoulder and having a tip for engagement with the lower face of the coin, said finger being offset downwardly from said shoulder and tip, said tip being offset laterally from said arm and shoulder.

Signed at Chicago this 6th day of August, 1927.

AXEL MONSON.
